UNITED STATES PATENT OFFICE.

ROBERT E. KIMBALL, OF CLEVELAND, OHIO, ASSIGNOR TO THE CLEVELAND FOLDING MACHINE COMPANY, OF CLEVELAND, OHIO, A CORPORATION OF OHIO.

PAPER-CONVEYING MECHANISM.

1,297,181.

Specification of Letters Patent.

Patented Mar. 11, 1919.

Application filed March 12, 1914. Serial No. 824,238.

To all whom it may concern:

Be it known that I, ROBERT E. KIMBALL, a citizen of the United States, residing at Cleveland, in the county of Cuyahoga and State of Ohio, have invented certain new and useful Improvements in Paper-Conveying Mechanism, of which the following is a specification.

My invention relates to improvements in paper-conveying mechanism, adapted for use in connection with paper-folding machines, and the like. The object of my invention has been to produce a conveyer acting upon folded sheets traveling edgewise, which will expeditiously pass the sheets from one section of the machine to another, without buckling or affecting their register, and which will not wrinkle or mar the sheets in any way.

20 In the patent to Johnson, No. 893,629, July 21, 1908, there is shown a conveying mechanism wherein a plurality of spaced rollers are set at an angle with the normal travel of the paper, between which the signature is adapted to open sufficiently to be passed downward into another portion of the folding machine.

It is necessary that these rollers shall be sufficiently separated so that the travel of the signature therebetween substantially at right angles to the rollers, will not be impeded, and in consequence, their action is not positive. There have also been provided in folding machine mechanism, certain diagonally positioned rollers, which are designed to effect the diagonal travel of the paper or signature, but the foregoing are distinguished from my invention by reason of the fact that a continuous supporting guide is provided immediately adjacent to rolls lightly engaging throughout a small periphery thereof, which permit a slight slippage of the signature as soon as the sheet is seated edgewise upon the guide or support.

45 The improvements of my invention comprise essentially paired engaging rolls, whose axes are slightly at an angle with the travel of the sheet, and which act in conjunction with a continuous stationary guide to retain the paper within or upon the guide and pass it rapidly along the same to another portion of the machine. Preferably these paired rolls are duplicated and positioned so that the paper is operated upon immediately it passes from the last co-acting set of rolls.

Also a spring adjustment is provided for causing the rolls to engage the paper with the desired pressure, depending upon the weight or thickness of the stock. The details of my improvement will be explained in connection with the accompanying drawings, showing the same in association with certain portions of a folding machine, sufficient to explain my invention.

Figure 1 of said drawings is an end view 65 of a machine equipped with my improvements; the same being shown partially broken away and in section.

Fig. 2 is a fragmentary horizontal section illustrating the driving gear.

Fig. 3 is a side view of the machine, also partially broken away.

Fig. 4 is an enlarged plan view of the horizontal conveyer rolls and their recessed guide.

Fig. 5 is a fragmentary vertical section thereof, and Fig. 6 is a fragmentary plan view of a pair of said rolls, sectioned to show their spring mounting.

Fig. 7 is an enlarged fragmentary inner 80 view of the adjustable bank of vertical conveyer rolls, and

Fig. 8 is a fragmentary view of a modified frusto-conical roll.

Throughout the several figures of the 85 drawings, I have employed the same characters of reference to indicate similar parts.

Referring first to Figs. 1 and 3, the course of the paper may be traced in order to afford an initial idea of the present improvement 90 and its purpose. We shall assume that the paper has received its primary fold or folds, and is passed to the vertical frame *a* from between the paired rolls *b*, *b'*; the co-acting rolls being hidden in Fig. 1. From the 95 frame *a*, the paper is passed to the right into the folding plate *c*, by means of the two sets of inclined horizontal rolls *d*, *e*. The folding plate *c* is set at an angle of forty-five degrees with the transverse travel of the 100 paper, from which it is passed through paired buckling rolls *f* and feed rolls *g*, to the vertical bank *h* of inclined rolls shown upon the left of Fig. 3, and by these the sheet is passed downward as finally folded, between 105 the lower delivery rolls *i*, *j*.

This bank *h* of rolls is horizontally adjustable toward and from the rolls *g*, according to the size of the sheet as finally folded. Since no improvement in the fold- 110

ing mechanism is herein claimed, the foregoing description will be ample for explaining my present improvement and its relation to any approved type of folding machine.

The several conveyer rolls of my invention preferably are of somewhat frusto-conical shape, better to receive the paper between them as it is advanced thereto. Figs. 10 5 and 6 well illustrate details of the mounting of the paired rolls *d*. Each is provided with a meshing-gear *d'*, adapted to drive the left-hand roll in clockwise direction, and its co-acting roll in opposite direction above a 15 grooved guide *k*. This left-hand roll is journaled in a frame *l*, mounted between opposing springs *l'*, *l''*; the latter having a screw-adjustment *l'* for compressing the spring *l''* sufficiently to react against the 20 pivot-post *m*, and cause the rolls *d* to engage the paper with precisely the desired pressure, dependent upon its weight and thickness. As best shown in Fig. 4, the groove *k'* is slightly recessed immediately beneath 25 the right hand rolls *e*, which are identical in construction and mounting with those just described; said rolls being positioned at an angle of five to ten degrees with the vertical, inclined toward the normal travel of the 30 paper.

It may be explained that the depression or recess *k''* within the groove *k'* preferably is provided for the purpose of maintaining the folded sheets in register and preventing 35 their buckling as they are seized or grasped by the paired rolls *e*. The depression *k''* is slight, being approximately five to ten thousandths of an inch below the surface of the groove *k'*. Nevertheless, it is 40 sufficient to accommodate the slight increase in the apparent width of the folded sheet as the edge is grasped and compressed between the rolls *e*, which are spring-pressed to secure sufficient pressure for rapidly conveying the sheets into the folding plate *c*. It will be appreciated that the folded edge of the paper is forced down upon the bottom of the groove by reason of the inclination of the rolls which cause the paper to 45 travel to the right. With relatively thin paper, the tendency, is to slightly buckle or bend the paper immediately beneath the rolls *e*, so that the register of the sheet is affected unless a slight depression *k''* is 50 provided at this point. The depression not only accommodates the small increase in the apparent width of the paper, but the depressed groove affords two points of support immediately in front and at the rear of the 55 position of the engagement between paired rolls *e*. Consequently, there is no tendency to tilt the paper out of the plane of the groove and its travel in a right line toward the folding plate.

60 In Fig. 8 I have shown a slightly modified

type of frusto-conical roll which is especially adapted for use with thinner paper stock. The base *t* of the roll presents a smooth cylindrical face, while the upper portion *t'* is frusto-conical and merges into 70 the cylindrical portion of the roll. This portion *t'* is longitudinally milled or scored better to pass the paper between the rolls. Since these rolls are inclined, while the co-acting guide is stationary, there must be a 75 slight slippage between the paper and rolls, after the folded edge of the paper is seated within the groove. Consequently the cylindrical engaging portions of the rolls preferably are smooth and the paired rolls are 80 lightly and resiliently pressed together, in order to advance the paper without buckling or affecting the register. This type of roll may be substituted in either the vertical or horizontal banks of rolls, for those shown in 85 the other figures of the drawings.

The normal action of the paired rolls *d* and *e* is to seize the lower edge of the folded sheet immediately it leaves the paired rolls *b'*, between the converging faces of the 90 paired rolls *d*, *e*, which are power-driven by the gear *n*, to pass the sheet to the right from between the paired rolls *e*. By reason of their inclination, both sets of rolls tend immediately to seat the lower edge of the 95 paper evenly within the groove *k'*, and the rolls *e* pass said sheet into the folding plate *c* at the desired level, and in perfect register. The guide *k*, it may be noted, together with the paired rolls *d*, *e*, is made vertically adjustable merely by loosening the bolt *o*, which releases the strap *o'*, engaging the vertical supporting bar *o''*.

The vertical bank of rolls *h* comprises a plurality of paired rolls identical in construction with the rolls *d* above described. These co-act with a grooved vertical guide *h'* to pass the folded sheets downward between the paired guides *p* and the delivery rolls *i*, *j*. The details of construction and the operation of the bank of rolls requires no specific explanation, but it should be pointed out that the supporting frame *q* is adjustably carried upon the bar *q'*, so that the bank of rolls may be advanced toward the 105 feed rolls *g* in position to seize the folded sheet, depending upon its width, as it is released from rolls *g*. The supporting frame *q* is mounted upon a split sleeve *r*, engaging the rod *q'*; which sleeve is adapted to 110 be clamped in any adjusted position thereon by means of the transverse bolt *r'*. The drive for said bank of rolls is shown in the enlarged fragment, Fig. 7, which comprises a meshing gear *s*, splined upon the shaft *s'* 115 and suitably connected with the common drive of the machine, by the gear *s''*, of which further details are unessential to the understanding of my invention. In certain 120 of the following claims I have used the 130

terms continuous support or guide, meaning thereby the substantially continuous support afforded by the guide herein for the edge of the paper, both to the rear and in front of 5 the coacting engaging rolls.

Having now set forth the preferred embodiment of my improvement, and explained the operation thereof in general terms, I claim as new and desire to secure 10 by Letters Patent, the following:

1. In paper-conveying mechanism, the combination with a guide having a continuous supporting face adapted to receive the edge of the folded sheet, of paired engaging 15 rolls positioned intermediately of the guide, the axes of which are set at an angle with said guide, and means for driving said rolls to seat and advance the paper longitudinally of the guide, substantially as set 20 forth.

2. In paper-conveying mechanism, the combination with a guide having a continuous groove therein, of a plurality of terminally divergent rolls positioned 25 between the ends of the guide and engaging immediately above the said groove; the axes of which are set at an angle with the plane of the groove, and means for rotating the rolls in unison to seat and advance the 30 paper edgewise within the groove, substantially set forth.

3. In paper-conveying mechanism, the combination with a guide having a continuous groove therein, of a plurality of 35 rolls engaging immediately above the said groove; the axes of which are set at an angle with the plane of the groove, said groove being depressed immediately adjacent to the meeting faces of the rolls, and 40 means for rotating the rolls in unison to seat and advance the paper edgewise within the groove, substantially as set forth.

4. In paper-conveying mechanism, the combination with a guide having a continuous groove therein, of a plurality of frusto-conical rolls positioned between the ends 45 of the guide and engaging immediately above said groove; the axes of which are set at an angle with the plane of the groove, and means for rotating the rolls in unison to seat and advance the paper edgewise within the groove, substantially as set forth.

5. In paper-conveying mechanism, the combination with a guide having a continuous groove therein, of a plurality of frusto-conical rolls, engaging immediately 50 above the said groove; the axes of which are set at an angle with the plane of the groove, said groove being depressed immediately adjacent to the meeting faces of the rolls, and means for rotating the rolls in unison to seat and advance the paper edgewise within the groove, substantially as set 55 forth.

6. In paper-conveying mechanism, the

combination with a grooved guide, of a plurality of co-acting rolls engaging immediately above the grooved guide, whose axes are set at a common angle therewith, means for adjusting the guide and rolls in the 70 plane of their axes, and driving mechanism for rotating the rolls in unison to seat and advance the paper edgewise within the grooved guide, substantially as set forth.

7. In paper-conveying mechanism, the combination with a guide having a continuous supporting face adapted to receive the edge of the folded sheet, of paired rolls positioned adjacent to the guide intermediate its ends and engaging immediately 80 above the guide; the axes of said rolls being at a common angle with the plane of the guide, a journal bearing for one of said rolls, a spring adjustment acting thereon for engaging said roll with its co-acting 85 roll, and means for driving said rolls in unison, substantially as set forth.

8. In paper-conveying mechanism, the combination with a grooved guide, of paired frusto-conical rolls engaging immediately 90 above the groove, a journal bearing for one of said rolls, two opposing springs respectively acting thereon, an adjustment for controlling the engaging-pressure of the rolls, and means for driving said rolls in unison, 95 substantially as set forth.

9. In paper-conveying mechanism, the combination with paired frusto-conical rolls, of a grooved guide extending longitudinally between said rolls with which their 100 axes are set at an inclination; said grooved guide being slightly recessed immediately beneath the engaging point of said rolls, and driving mechanism for rotating the rolls in unison to seat and advance the paper 105 edgewise within the grooved guide, substantially as set forth.

10. The combination with a folding machine, of paper-conveying mechanism therein, comprising a grooved guide, a bank of 110 associated paired rolls, engaging immediately above the groove, means for adjusting the guide and rolls with respect to the folding machine, spring adjusting means for varying the pressure of the rolls; said rolls 115 being set with their axes inclined to the plane of the groove, and driving mechanism for rotating the bank of rolls in unison to seat and advance the paper edgewise within the grooved guide, substantially as set 120 forth.

11. In paper-conveying mechanism, the combination with a guide having a continuous supporting face adapted to receive the edge of the folded sheet, of paired co-acting 125 rolls, the axes of which are slightly inclined toward the direction of travel for the folded sheet; said rolls having substantially cylindrical sections engaging immediately above the guide and frusto-conical upper 130

sections, resilient means for engaging the rolls, and driving mechanism for rotating the rolls in unison to seat and advance the sheet longitudinally of the guide, substantially as set forth.

12. In paper-conveying mechanism, the combination with means for passing sheets in a given direction, of a guide having a continuous supporting face substantially at right angles to the initial travel of the paper, spring-pressed engaging rolls, the axes of which are set at a slight angle with the path of the paper during its secondary movement; said rolls having terminally divergent frusto-conical upper portions and cylindrical lower portions adapted positively to engage and advance the paper therebetween, and means for driving said rolls to seat the paper accurately upon the guide, substantially as set forth.

13. In paper-conveying mechanism, the combination with a guide affording a continuous supporting face, of a plurality of frusto-conical rolls peripherally engaging immediately above the guide; said guide being recessed adjacent to the meeting faces of the rolls, a spring mounting for said rolls, and means for rotating said rolls in unison to seat and advance the paper edge-wise upon the guide, substantially as set forth.

14. In paper-conveying mechanism, the

combination with a horizontal guide affording a continuous supporting face for the edge of the paper, of paired spring-pressed rolls intermediately positioned with respect to said guide and engaging each other peripherally immediately above the guide in position to grasp the paper near its edge; said rolls being set at a slight angle with the vertical and adapted to seat the paper and advance it along said guide, and means for rotating the rolls in unison, substantially as set forth.

15. In apparatus of the class described, the combination with paired engaging rolls, of an associated horizontal guide for the edges of the signatures conveyed; said rolls being positioned closely adjacent to the supporting plane of the guide with their axes slightly inclined toward one end thereof and said guide extending laterally in both directions beyond the rolls for supporting and accurately positioning the signatures, means for driving said rolls, and yielding mechanism for lightly pressing them into engagement, substantially as set forth.

In testimony whereof I do now affix my signature in the presence of two witnesses.

ROBERT E. KIMBALL.
